UNITED STATES PATENT OFFICE.

WILLIAM T. SMITH, OF PHILADELPHIA, PENNSYLVANIA.

DESIGN FOR WOVEN FABRIC.

SPECIFICATION forming part of Design No. 28,372, dated March 8, 1898.

Application filed January 21, 1898. Serial No. 667,494. Term of patent 7 years.

To all whom it may concern:

Be it known that I, WILLIAM T. SMITH, a citizen of the United States, residing at Philadelphia, in the county of Philadelphia and State of Pennsylvania, have invented and produced a new and original Design for a Woven Fabric, of which the following is a specification, reference being had to the accompanying drawing, making a part of the same.

The leading features of my design are the representation of a peacock with folded tail and resting on a balustrade, a mountain in

the background, trees and castle on a hill to the right, with a floral representation at the base, the whole surrounded by a floral border, as shown.

Having as above fully described my invention, what I claim as new, and desire to secure by Letters Patent, is—

The design for a woven fabric, as shown in the accompanying drawing.

W. T. SMITH.
